UNITED STATES PATENT OFFICE

CHARLES SEBASTIAN BICHELE, OF CHICAGO, ILLINOIS, ASSIGNOR TO J. MILHENING, INC., OF CHICAGO, ILLINOIS, A CORPORATION OF ILLINOIS

DESIGN FOR A SCARFPIN

Application filed September 22, 1930. Serial No. 37,050. Term of patent 3½ years.

To all whom it may concern:

Be it known that I, CHARLES SEBASTIAN BICHELE, a citizen of the United States, residing at Chicago, in the county of Cook and State of Illinois, have invented a new, original, and ornamental Design for Scarfpins, of which the following is a specification.

In the accompanying drawing, forming part of the specification—

I claim:

The ornamental design for a scarfpin as shown.

CHARLES SEBASTIAN BICHELE.
